(57) **CLAIM**

The ornamental design for a defrosting sheet, as shown and described.

DESCRIPTION

FIG. 1 is a bottom perspective view of defrosting sheet showing my new design.

FIG. 2 is a top perspective view thereof.

FIG. 3 is a front view of the defrosting sheet in a folded condition.

FIG. 4 is a back view of FIG. 3.

FIG. 5 is a right-side view of the defrosting sheet in a folded condition; and,

FIG. 6 is a left-side view of the defrosting sheet in a folded condition.

Broken lines illustrated in the figures represent stitches and form part of the claimed design.

The thick dash-dot lines illustrated in bold in FIGS. 3 and 6 are part of the design.
